UNITED STATES PATENT OFFICE.

ELIOT SUMNER, OF NEW YORK, N. Y.

SUPERHEATER UNIT.

Application filed April 8, 1920. Serial No. 372,228.

This invention relates particularly to the type of superheater unit commonly used in locomotive boilers and in certain styles of stationary boilers, and in which a cluster of steam-pipe sections is mounted within a boiler fire-tube in the path of the fire-gases therein, and its object is to simplify and improve such units in respect to the assembly and mounting of the pipe sections thereof.

The accompanying drawings illustrate the principle of the invention showing it applied in its preferred form. Fig. 1 represents part of an ordinary locomotive boiler with two superheater units in place therein. Fig. 2 is a perspective of a single unit broken away in its central part, for convenience of illustration and Fig. 3 is an enlarged cross section of a unit showing the means for spacing and uniting the pipes.

In Fig. 1, the large pipe 4 delivers steam from the boiler proper to the compartment 3 of a manifold or superheater header. From this compartment the steam flows through each of a group of similar superheater units, located in the fire-tubes 5, and back to compartment 2 of the header and thence out through the pipe 1 according to the customary arrangement. Each superheater unit consists of several lengths or sections of steam pipe 6 connected together at their ends so as to form a flow path from one header compartment to the other. The steam passing through these pipes is superheated by the hot fire-gases passing from the fire box to the stack 7. In the case shown, each unit is a cluster of four pipe sections, which number is generally preferred though not essential; the diametrically opposite pipes are connected to each other at their rear ends by the return bends 8; the two upper pipes are connected at their forward ends by the return bend 9; and the forward ends of the two lower pipes are upturned as indicated at 10 for connection to the inlet and outlet compartments 3 and 2 above mentioned, thus forming a continuous steam path running back and forth through the fire tube. Such a path can obviously be formed by different arrangements of the return bend in all which arrangements this invention is adapted for use as will presently appear. It is important that the pipes constituting the unit shall be so supported as to be exposed to the flow of the hot gases over the entire exterior surface of each pipe, and that their supporting and spacing means shall offer

minimum obstruction to the gaseous flow, and these means must also be permanently secure when assembled with their pipes so that under the effect of thermal expansions and vibration and also in the process of removing and replacing the units, within the larger tubes, they will not work loose and allow the pipes to sag into contact with the fire-tube or each other, which diminishes the surface exposure besides promoting the collection of dust and cinders which impairs the gas flow and the efficiency of the unit.

According to this invention the spacing and uniting devices of the unit are so combined with the pipes 6 as to utilize their elastic resistance to lateral flexure as the means of keeping the devices tight and thus keeping the pipes properly located under all conditions. Spacing means acting on this principle can be variously formed and applied and can be readily so made as to present a negligible obstruction to the fire-gas flow besides possessing other advantages as will presently appear.

According to this invention the spacing and uniting means shown in the drawing consist of a pair of strap loops 11 and 12. The loop 11 is formed by a piece of strap iron passed around the diagonally opposite pipes and between and in contact with the other two pipes and riveted together at its ends. The similar loop 12 in like manner is passed around the two last mentioned pipes and between and in contact with the two others and similarly riveted together at its ends. In this crossing relation each loop serves to bind together two pipes and at the same time spaces apart the other two. When these or equivalent tying or cross-tying members are first applied to the pipes which they respectively embrace, the latter are drawn or bent inwardly or toward each other so that their elastic tendency to resume their normal condition of straightness keeps the loops or members under tension and this keeps the latter firmly but non-rigidly secured in the positions in which they have been put and in great measure eliminates the possibility of their working loose, and by such an arrangement the four pipes are bound tightly and held in proper relation to each other, without the use of any additional connecting pieces, and such band can be made of lighter material than other forms of bands, without sacrificing strength. By the accommodation to thermal contractions and expansions thus provided the assembly is practically perma-

uent. The convenient and simple method of fixing the loops in position and under adequate tension, is to bind them around their respective pipes when well separated from each other, lengthwise of the pipes, as indicated, for example, by the dotted line position of the strap 12 in reference to the full line strap 11 of Fig. 2, and then driving one strap toward the other along the pipes until a suitable degree of tension has been produced. Preferably the loops are left still slightly spaced from each other when the unit is first assembled, so that at some later time they may be driven closer together if further tightening should ever be required. It may be noted in passing that the pressure of each pair of pipes upon the mid portion of the loop of the other pair serves to equalize the degree of tension in all the members of the unit, and also that inasmuch as the strap-form loops lie edgewise to the flow, they space the pipes with a minimum obstruction.

It is a further feature of the invention that the riveted ends of the strap loops can be left projecting to form feet by which the unit rests on the wall of the fire-tube. Such feet are desirable but other forms of feet could obviously be used. Fillers 13 are shown between the riveted ends to provide a larger bearing surface but are not essential. The two pieces marked 14 in Fig. 3 are merely short extra pieces of strap iron riveted to the respective loops to space the lower pipes somewhat further apart than the upper pipes and the purpose of this greater separation is to provide an ample escape for cinders which might otherwise lodge and accumulate inside the pipe cluster. This feature is likewise desirable, but as will be observed is also subordinate to the main idea. It will now be obvious that as many pairs of loops or pipe-connecting members may be used on each superheater unit as its length and the size and number of steam pipes in the cluster may require, and that various dispositions of said members and different forms thereof will also provide some or all of the benefits of the invention as above described. All of which are intended to be included individually and collectively in the following claims.

Claims:—

1. A superheater unit comprising a plurality of substantially parallel pipes and means for spacing and uniting them comprising pairs of members, such pairs being placed at intervals along the lengths of said pipes, the members of each pair occupying

adjacent planes and one member serving to space two pipes apart and the other to pull them together, thereby exerting a bending strain on the pipes which retains said members in place.

2. A superheater unit comprising a cluster of pipes occupying a fire-tube or passage and means for spacing apart two of said pipes comprising a strap loop uniting and held in tension by others of said pipes.

3. A superheater unit comprising a cluster of pipes and means for spacing said pipes from each other comprising a strap loop uniting and inwardly stressing two pipes, and a second strap loop uniting two pipes and inwardly stressing one of them against the first mentioned strap loop.

4. A superheater unit comprising a cluster of pipes and means for spacing them apart and supporting the cluster in a fire tube, comprising a strap loop uniting and inwardly stressing two pipes, and a second strap loop uniting two pipes and inwardly stressing one of them against the first mentioned loop; one of said loops being provided with a foot to engage the fire tube.

5. A superheater unit comprising a cluster of four pipes and means for spacing them in fixed relation comprising two adjacent strap loops each inwardly stressing two diagonally opposite pipes and outwardly stressing the two others.

6. The method of securing the pipes of a superheater unit in fixed relation which comprises assembling on the unit, in longitudinally separated positions, a member adapted to resist inward displacement of two of the pipes and a member adapted to resist outward displacement of said pipes and then setting up bending strains in said pipes by forcing said members longitudinally along the unit into less separated positions thereon.

7. The method of securing the pipes of a superheater in fixed relation which comprises assembling in longitudinally separated positions a member on one group of said pipes arranged to resist relative inward displacement of the pipes of a second group and a second member on said second group of pipes arranged to resist the relative inward displacement of the pipes of the first mentioned group, and then setting up bending strains in said pipes by forcing said members longitudinally along the respective pipes into less separated positions thereon.

In testimony, whereof, I have signed this specification.

ELIOT SUMNER.
